UNITED STATES PATENT OFFICE.

GEORGE McCONNELL, OF GRAND RAPIDS, MICHIGAN.

GLUING-MACHINE.

1,399,975.

Specification of Letters Patent. Patented Dec. 13, 1921.

Application filed December 7, 1920. Serial No. 428,884.

To all whom it may concern:

Be it known that I, GEORGE McCONNELL, a citizen of the United States of America, residing at Grand Rapids, in the county of 5 Kent and State of Michigan, have invented certain new and useful Improvements in Gluing-Machines; and I do hereby declare the following to be a full, clear, and exact description of the invention, such as will enable others skilled in the art to which it 10 pertains to make and use the same.

This invention relates to gluing machines and more particularly to such machines adapted to spread glue upon the surface of 15 boards or other objects to be glued together. It is the object of this invention to provide a machine which will successfully apply either the so called vegetable glue or the animal glue, one being more fluid than the 20 other, to the object to be glued, to provide simple and easily adjusted means for changing the machine to operate on either the thick or thin glue or to spread a thicker or 25 thinner coating of either kind, to provide a machine which is always ready to apply glue to the surface of an object without 30 waiting for any cycle of operations to take place and to provide such a machine which is simple in construction and operation, economical in the use of glue, and substantially 35 built. The device is provided with other new and useful features of construction and arrangement which will more fully appear as an understanding of the invention is had 40 from the following description, taken in connection with the accompanying drawings in which:

Figure 1 is a side elevation, partly in section, of a device embodying this invention.

Fig. 2 is a transverse sectional elevation of the same on the line 2—2 of Fig. 1.

Fig. 3 is an enlarged plan view on the line 3—3 of Fig. 1 of the glue roll driving and reverse gears.

Fig. 4 is an enlarged elevation of one of the chain sprockets and a portion of the glue spreading chain and supporting track, and

Fig. 5 is a transverse section of said 50 sprocket and chain on the line 5—5 of Fig. 4.

Like reference characters refer to like parts in all of the figures of the drawings.

The frame of the machine, preferably rec- 55 tangular in shape, comprises the legs 1 and cross members 2. Near the upper part of

the frame and near each of its respective ends are located sprocket wheels 3 mounted on shafts 4, journaled in bearings 5, attached to the cross members 2 of the frame. 60 A specially constructed glue spreading chain 6 runs over said sprockets and comprises the spreading links 7 and connecting links 8. Each of the spreading links has a body portion 9 comparatively thin and provided with 65 ears 10 near its respective ends through which the rivets 11 pass, said rivets serving to attach the connecting links 8 which are arranged in pairs on opposite sides of said body portion 9 of the spreading links. 70 Each spreading link also has a face portion 12 extending at right angles to the body portion 9 and lying in a horizontal plane in that portion of the chain, both top and bottom, which extends between the sprockets 3. 75 The peripheries of the sprockets 3 are slightly thinner than the body portions 9 of the links 7 and are serrated, the extending portions 13 of said serrations serving as sprocket teeth which extend between the ears 80 10 of the chain as said chain passes over the sprockets. The sprockets 3 also have adjacent thin serrated edges, oppositely extending flanges 14 which engage and support the connecting links 8 as the chain passes over 85 the sprockets. A supporting track 15 is located beneath the upper portion of the chain, being preferably supported by the bars 16 and extends between the sprockets 3. The track is adapted to support the upper portion 90 of the chain which extends between the sprockets, in a level horizontal plane, the connecting links 8 engaging the upper surface of the track and traversing the same as the chain moves.

Glue is supplied to the face portions 12 of the chain from a glue pot 17 located near the lower part of the machine, a glue roller 18 mounted on a shaft 19 journaled in bearings 19^a, runs with its lower portion immersed in the glue and its upper surface is engaged by the face 12 of the lower portion of the chain as it moves about the sprockets 3.

Owing to the different consistency of different kinds of glue used, and for the purpose of applying the glue in a thick or thin coating on the face 12 of chain, it is desirable to rotate the glue roller 18 at times with its surface contacting the face of the chain 110 moving in the same direction and at approximately the same speed as said chain

and at other times to rotate said roller in the opposite direction. The roller is rotated and its change of direction effected through the gears 20, 21 and 22, the sprockets 23 and 5 24 and the drive chain 25. The sprocket 24 is fixed to one of the shafts 4 on which a sprocket 3 is mounted and said shaft is rotated by any convenient means, a pulley 26 being shown fixed to the shaft over which a 10 belt may be run. A shaft 27 is journaled in one end of an arm 28 and the other end of said arm is pivotally attached to the frame of the machine. The sprocket 23, driven by the chain 25 from the sprocket 24, is attached to the shaft 27 at one side of said arm and the gear 22 is attached to said shaft at the other side of the arm. The gear 20 is 15 fixed to the glue roller shaft 19 and the idler gear 21 meshes with the gear 20 and is mounted on the frame 2. The driven gear 22, by virtue of being mounted at the end of the pivoted arm 28, may be moved to mesh with and drive either the idler gear 21 or the gear 20. By driving directly the 20 gear 20, the roller 18 is caused to rotate in one direction and by driving said gear 20 through the idler gear 21, the roller is caused to rotate in the opposite direction. A slotted extension 29 on the arm 28 having a clamping bolt 30 passing through the slot therein permits the said arm 28 to be clamped in either of its positions.

A top or cover 31 having a longitudinal slot through which the upper part of the 35 chain 6 projects is supported by the frame 2, its surface being slightly below the face 12 of the chain.

The operation of the machine is very simple. The driving shaft 4 is rotated by any 40 convenient power and the glue spreading chain 6 passing over the sprockets 3 is moved, its lower portion passing over and in engagement with the glue roller 18 and its upper portion, being supported in a horizontal plane by the track 15, is constantly 45 changing as the links freshly supplied on their faces 12 with glue from the roller 18 pass over the sprocket 3 and into view through the slotted top 31. The glue roller 50 is driven as above described, either in the same direction as the chain or in the opposite direction, thereby applying either a thick or thin coat of glue to the face of the chain. A board 32 or any object to which 55 glue is to be applied is placed manually with the surface to be glued in contact with the upper face 12 of chain and receives by such contact the proper coating of glue for the purpose it is to be used.

60 Since there is no cycle of operations to be followed in order, the machine, after being set in motion, is always ready for instant use and there is continuously appearing a freshly glued surface of chain from which 65 to receive glue. Therefore the operator may

work as rapidly as he desires without interruption.

While a specific construction has been shown and described, it will be obvious that many changes may be made in the structure 70 without departing from the spirit of the invention.

I claim:

1. A gluing machine comprising a movable glue-spreading member, a glue receptacle, 75 a glue roller partly immersed in glue in said receptacle and engaging the surface of said glue spreading member to apply glue thereto and means for rotating said roller in either direction so that its periphery in engagement 80 with said member moves in the same direction as the member or in the opposite direction thereto.

2. A gluing machine comprising a movable glue-spreading member, a glue receptacle, a glue roller fixed to a shaft and partly immersed in glue in said receptacle and engaging the surface of glue spreading member, a gear fixed to said glue roller shaft, an idler gear meshing with said gear on the glue 90 roller shaft, a pivoted arm, a driving gear journaled on said arm and adapted to be moved to mesh with and drive either said gear on the glue roller shaft or said idler gear, and means for rotating said driving 95 gear.

3. A gluing machine comprising sprockets mounted on shafts, an endless glue-spreading chain running over said sprockets, a glue receptacle, a glue roller fixed to a shaft and 100 partly immersed in glue in said receptacle and engaging the surface of said chain, a gear fixed to said glue roller shaft, an idler gear, meshing with said gear on the glue 105 roller shaft, a pivoted arm, a driving gear journaled on said arm and adapted to be moved to mesh with and drive either the said gear on the glue roller shaft or the said idler gear, means for driving one of said sprocket shafts and means for driving said driving 110 gear from said sprocket shaft.

4. A gluing machine comprising a chain running over sprockets, said chain comprising glue spreading links and connecting links, said glue spreading links having thin 115 body portions to which the connecting links are attached and broad face portions extending at right angles to the body portions and adapted to be engaged by the object to be glued and means for applying glue to said 120 face portions of the glue-spreading links.

5. A gluing machine comprising sprockets, a chain running over said sprockets comprising glue-spreading links and connecting links, a track extending between said sprockets and adjacent said chain and engaged by said connecting links thereof to maintain the links in alignment and means to apply glue to the glue-spreading links.

6. A gluing machine comprising a chain 130

having glue-spreading links and connecting links, sprockets over which said chain runs having shoulders near their peripheries which engage and support said connecting 5 links and means for applying glue to said glue-spreading links.

7. A gluing machine comprising a chain having glue-spreading links and connecting links, said glue-spreading links having thin 10 body portions with ears thereon, and said connecting links being disposed in pairs on

opposite sides of said ears and attached thereto, sprockets having serrated peripheries, the extensions of such serrations adapted to fit between said ears and also between the links of each pair of connecting links, shoulders on said sprockets near their peripheries to engage and support said connecting links and means for applying glue to said glue-spreading links. 15

In testimony whereof I affix my signature.

GEORGE McCONNELL. 20
